UNITED STATES PATENT OFFICE.

CHAMP J. BARTH AND JOSEPH RAYMOND PIERCE, OF MINNEAPOLIS, MINNESOTA.

DESIGN FOR A RING.

Application filed February 20, 1923. Serial No. 5,218. Term of patent 7 years.

To all whom it may concern:

Be it known that we, CHAMP J. BARTH and JOSEPH R. PIERCE, citizens of the United States, residing at Minneapolis, in the county of Hennepin and State of Minnesota, have invented a new, original, and ornamental Design for a Ring, of which the following is a specification, reference being had to the accompanying drawing, forming part thereof.

The figures are, respectively, a plan and edge view of a ring, showing our new design.

We claim:

The ornamental design for a ring, as shown.

CHAMP J. BARTH.
JOSEPH RAYMOND PIERCE.
